UNITED STATES PATENT OFFICE.

EDWARD F. COLLINS, OF INDIAN ORCHARD, MASSACHUSETTS.

DESIGN FOR AN EMBLEM.

49,572.

Specification for Design. Patented Aug. 29, 1916.

Application filed June 17, 1916. Serial No. 104,283. Term of patent 14 years.

To all whom it may concern:

Be it known that I, EDWARD F. COLLINS, a citizen of the United States of America, residing at Indian Orchard, in the county of Hampden and State of Massachusetts, have invented a new, original, and ornamental Design for Emblems, of which the following is a specification, reference being had to the accompanying drawing, forming part thereof.

The figure is a front elevation of an emblem, showing my new design.

I claim:

The ornamental design for an emblem, as shown.

EDWARD F. COLLINS.
